(57) **CLAIM**

The ornamental design for a mosquito trap, as shown and described.

DESCRIPTION

FIG. 1 is a perspective view of a mosquito trap of my new design.

FIG. 2 is a front elevation view of the trap of FIG. 1.

FIG. 3 is a rear elevation view of the trap of FIG. 1.

FIG. 4 is a right side view of the trap of FIG. 1.

FIG. 5 is a left side of the trap of FIG. 1.

FIG. 6 is a top view of the trap of FIG. 1; and,

FIG. 7 is a bottom view of the trap of FIG. 1.

The broken lines in the drawings are included for the purpose of illustrating unclaimed features and form no part of the claimed design.

1 Claim, 7 Drawing Sheets

FIG. 1

FIG. 2

FIG. 3

FIG. 4

FIG. 5

FIG. 6

FIG. 7
